UNITED STATES PATENT OFFICE.

GEORGE A. LANCIAUX, OF INDIAN ORCHARD, AND OLIVER F. SMITH, OF SPRINGFIELD, MASSACHUSETTS.

BABY-CARRIAGE.

SPECIFICATION forming part of Letters Patent No. 642,464, dated January 30, 1900.

Application filed May 29, 1899. Serial No. 718,717. (No model.)

To all whom it may concern:

Be it known that we, GEORGE A. LANCIAUX, a resident of Indian Orchard, and OLIVER F. SMITH, a resident of Springfield, in the county of Hampden and State of Massachusetts, citizens of the United States of America, have invented certain new and useful Improvements in Baby-Carriages, of which the following is a full, clear, and exact description.

10 This invention relates to improvements in baby-carriages of the class in which the pair of forward wheels thereof are smaller than the rear wheels and are separately mounted in swiveling forks, whereby it becomes possible to turn the carriage completely or partly around by sidewise pressure on the push-handle without the necessity of pressing down upon the latter to elevate the front wheels clear of the ground, as most commonly practiced where the front wheels are both carried upon the end of the front axle.

15 The present invention particularly relates to the new specific means employed whereby the swiveling forks for the front wheels are journaled upon the opposite bars comprised in the supporting-frame for the carriage, the said device to this end being of extreme simplicity and cheapness and permitting most readily the assemblage or displacement of the

20 parts for repair, lubrication, or replacement or substitution; and the invention consists in the construction and combination of parts, as specifically described, shown, and set forth in the claim.

25 Reference is to be had to the accompanying drawings, in which this invention is illustrated.

Figure 1 is a side elevation of a baby-carriage, showing the improved mounting for the 40 swivel-forks at the front thereof. Fig. 2 is a front view and partial vertical section. Fig. 3 is a plan view of the front end portion of one of the side bars comprised in the carriage-body, inverted, showing the improved bracket 45 or casting in which the stem of the fork is applied. Fig. 4 is a partial front view of one of the forks and its stem, the latter being partially in central section, together with the retaining device. Fig. 5 is a perspective view 50 of the bracket or casting aforementioned.

Similar characters of reference indicate corresponding parts in all of the views.

In the drawings, A represents the carriage-body spring-supported above the carriage-frame B, as usual, said frame comprising the 55 lower horizontal parallel longitudinally-extending bars or members *a a*, and said frame is at the rear united by the transverse axle *b* for the large rear wheels C.

D represent the pair of smaller front 60 wheels arranged outside of the bars *a a*, they being mounted in the forks F F, each of which at its upper part is provided with the upwardly-extended stem *d*, which protrudes and has its journal-bearing for rotation within the 65 vertical hollow hub-like member *f* of the cast-iron bracket or fork support G. The said casting G comprises the flat member *g*, which is adapted to lie against and longitudinally under and along the forward portion of the 70 bar *a*, being firmly secured thereto by screws or bolts, as indicated at *g*², and, furthermore, comprises the angular outwardly-extending horizontal member *h*, at the outer extremity of which the aforesaid upstanding roller-hub 75 *f* is supported as an integrally-provided part thereof.

The stem of the fork F is preferably, and as shown in Fig. 4 at 10, necked down between its upper and lower ends, leaving the 80 larger comparatively short cylindrical portions 12 12 thereof to constitute adequate journals without unnecessary length of bearing for undue friction. The upper end of the stem is provided with a vertical screw-tapped 85 socket 13, in which the threaded stem 14 of the shouldered retainer-screw *i* engages.

We are aware that baby-carriages have been proposed in which the wheels thereof were in a way mounted in forks adapted to 90 swivel in somewhat the same manner as do the forks herein described and shown, and such we do not broadly claim; but

What we specifically claim, and desire to 95 secure by Letters Patent, is—

In a baby-carriage, the combination with the carriage-frame comprising the horizontal parallel longitudinal bars *a a*, and the uniting rear axle having the large rear wheels mounted thereon, of the castings or brackets G each 100

of which comprises the flat longitudinal member *g*, which is secured under the forward end portion of one of said bars, the horizontal outwardly-extending member *h*, and the integrally-formed upstanding hollow hub-like member *f*, of the fork *F*, for each of the pair of smaller front wheels, provided with the upstanding stem *d* extending and journaled

within the said hollow member *f*, and the retainer *i*, all substantially as described and shown.

GEO. A. LANCIAUX.
OLIVER F. SMITH.
